INVENTOR

Edward J. Brooks

BY

ATTORNEY

UNITED STATES PATENT OFFICE.

EDWARD J. BROOKS, OF EAST ORANGE, NEW JERSEY.

SEALING MEANS

1,283,062.

Specification of Letters Patent. Patented Oct. 29, 1918.

Application filed June 8, 1918. Serial No. 239,073.

To all whom it may concern:

Be it known that I, EDWARD J. BROOKS, a citizen of the United States, and a resident of East Orange, in the county of Essex and State of New Jersey, have invented certain new and useful Improvements in Sealing Means, of which the following is a specification.

The present invention relates generally to sealing means for use in connection with containers, such as boxes, and more especially in connection with that kind of container known as a bale and used particularly in shipping the clothing of soldiers. It will be understood that it is advantageous to compress such bales into the smallest possible space and to have sealing means that will securely hold, and prevent expansion of the bale during transit.

The object of this invention is to produce a device that will securely fasten the opposed free ends of a strap and seal it in such manner as to hold the bale to its shape.

This invention consists principally in closing the overlapping free ends of a strap, of sheet metal or other suitable material, within the closed lateral edges of a flat tubular sealing member, having substantially parallel bends, the closed lateral edges of the sealing member, but not the body thereof, being then upset by a die to form oppositely extending crimps embedded in the lateral edge of the strap and extending at an angle to the parallel bends of the sealing member.

In the drawings there are shown several preferred embodiments of the invention, in which:

Figure 1 is a perspective view showing a container, such as a bale, with my invention applied.

Fig. 2 is a fragmentary view showing the free ends of the strap together with the sealing member.

Fig. 3 is an edge view of Fig. 2.

Fig. 4 is a detail view of the flat tubular sealing member.

Fig. 5 is a detail view showing a modified form of the sealing member.

1 indicates a container that may be of any suitable character and is here shown as a bale of flexible soft material, such as burlap, within which is packed the articles to be shipped. 2 is a strap of any suitable material, such as sheet metal, the free ends of which are caused to overlap and, in so doing, are inserted through the open ends 3 of a

flat tubular sealing member 4 which latter consists of a blank having parallel bends 5 and 6 that embrace the lateral edges of the overlapped portions of the strap. To securely fasten the parts together, the closed lateral edges of the sealing member, but not the body thereof, is upset to form oppositely extending crimps 7 embedded in the lateral edge of the strap and extending at an angle to the plane of the parallel bends of the sealing member and leaving an intervening flat body portion 10. In the preferred form of the construction, shown more particularly in Figs. 2 and 3, it will be seen that there is a plurality of crimps and that the adjacent crimps 7 of the same edge of the sealing member are upset in opposite directions with respect to the plane of the parallel bends of said member; and likewise the crimps 7 and 7^a of the opposed edges of the sealing member are staggered, when the parts are viewed edgewise, as is best seen in Fig. 3. The sealing member may be of any suitable character, such as is indicated in Fig. 4, where the bend 6 is in the nature of wings formed in the blank that constitutes the sealing member; while in Fig. 5, blank 4 is constructed with wings 8 and 8^a, one of which extends all the way across the width of the sealing member and the other one of which slightly overlaps the first one, as shown.

In Fig. 1, the bale 1 is shown as being secured by four of the sealing devices described, thereby securely holding and preventing the bale from expanding during transit.

Tests show that by upsetting the edges into crimps in the manner indicated there is formed not only a relatively flat seal of small bulk, since the upset portions 7 and 7^a project but slightly from the plane of the strap and sealing member, but a very strong seal that is capable of withstanding great pressure.

Another advantage of the flat body portion and crimped edge portion is that a die of standard construction, having opposed die members that crimp the metal up and down instead of squeezing the metal bodily edgewise, may be used.

I claim:

1. Sealing means comprising: a strap the free ends of which overlap, and a sealing member consisting of a sheet metal blank having substantially parallel bends forming

closed lateral edges embracing the lateral edges of the strap, said closed lateral edges of the sealing member being upset to form a plurality of crimps on each edge embedded 5 in the lateral edges of the strap, the adjacent crimps of the same edge being upset in opposite directions with respect to the plane of the parallel bends of the sealing member.

2. Sealing means comprising: a strap the 10 free ends of which overlap, and a sealing member consisting of a sheet metal blank having substantially parallel bends forming closed lateral edges embracing the lateral edges of the strap, said closed lateral edges

of the sealing member being upset to form a 15 plurality of crimps on each edge embedded in the lateral edges of the strap, the adjacent crimps of the same edge being upset in opposite directions with respect to the plane of the parallel bends of the sealing 20 member and the crimps of opposed edges being staggered with respect to the plane of the parallel bends of the sealing member when the device is viewed edgewise.

Signed at New York, in the county of 25 New York and State of New York, this 7th day of June 1918.

EDWARD J. BROOKS.
